UNITED STATES PATENT OFFICE

ABRAHAM ROSEN, OF ROCHESTER, NEW YORK.

LOCK FOR GARTERS.

1,332,955.

Specification of Letters Patent.

Patented Mar. 9, 1920.

Application filed March 12, 1919. Serial No. 282,231.

To all whom it may concern:

Be it known that I, ABRAHAM ROSEN, a citizen of the United States, residing at Rochester, in the county of Monroe and State of New York, have invented certain new and useful Improvements in Locks for Garters, of which the following is a specification.

The object of this invention is to provide 10 a new and useful locking device for garters, which is adapted to hold the garter locked after the garment has been placed in engagement therewith and which prevents the disengagement of the garment therefrom.

15 This and other objects of this invention will be illustrated in the drawings, described in the specification and pointed out in the claims at the end thereof.

In the drawing, Figure 1 is a perspective 20 view of the garter and its locking device, the parts being shown open.

Fig. 2 is a horizontal section through the garter and its locking device, the section being taken on the line 2^x—2^x of Fig. 1.

25 Fig. 3 is a perspective view of the garter and its locking device, the parts being shown closed.

In the drawings, like reference numerals 30 indicate like parts. The garter comprises a plate 1 having an opening 2 therein through which the elastic is inserted and fastened and having an opening 3 therein which receives a portion of the stocking that is to be supported by the garter. With the opening 35 3 engages a button 4 having a base 5 on which is mounted the stem 6 having an enlarged head 7. The button is placed on one side of the stocking and the plate 1 is placed on the other side of the stocking with the 40 enlarged upper end of the opening 3 in line with the head 7 of the button. The head of the button is then pushed through the opening, carrying a portion of the garment with it and the button and plate are then moved 45 relatively until the stem or shank 6 of the button rests in the lower part of the slot 3, in which position it is desired to fasten it permanently.

For this purpose I provide a dog 8 pivoted at 9 on the plate 1. This dog is shown 50 drawn to one side in Fig. 1 for the purpose of permitting the insertion of the button. After the button has been inserted as above described, the dog is moved in the position 55 shown in Fig. 3, in which position it covers the upper part of the opening 3 and pre-

vents the removal of the button therefrom, it being understood that the lower part of the opening 3 is narrower than the diameter of the head of the button and this prevents 60 the removal of the button therefrom.

The dog 8 has a projection 10 struck up therefrom which engages with the depression 11 formed in plate 1 which prevents the dog from turning when it is in mid position 65 as shown in Fig. 3.

To limit the swing of the dog I provide 70 the up-turned end 12 thereon which engages with the slot 2 and travels therein so that by its engagement therewith the dog is limited 75 to a movement on either side of the center to uncover the opening 3 and is held from going beyond that position. It is, therefore, held in a position that is most convenient for use, and from which it can be moved 80 easily to locking position.

The lower side of the slot 2 is curved to 85 conform to the path of travel of the up-turned end 12. The upper side of the slot 2 may be left straight to afford a convenient bearing for the elastic braid that is attached thereto and forms a part of the garter. The button 4 is also attached to an extension of the elastic braid of suitable length so that it is held in position for ready use. 85

The operation of the device is as follows: 90 The button 4 is placed on one side of the stocking and the plate 1 is placed on the other side of the stocking and the parts are moved so as to engage the button with the slot 3 and move it to the bottom thereof, carrying a portion of the stocking therewith into the slot, so that it remains interposed between the button and the plate. The dog is then moved from the position at one side 95 to the central position, in which position it will lock itself as above described, holding itself in that position until the dog and plate are slightly sprung apart at the bottom to permit the rotation of the dog from the position shown in Fig. 3 to the position 100 shown in Fig. 1, after which the fastener can be opened and removed from the garter.

I claim:

1. In a garter, the combination of a plate, 105 having an elongated slot therein, a button having a head thereon for engagement with said slot, and a dog pivoted on said plate, said dog being capable of covering a part of said slot to hold the button in the balance 110 of the slot, said plate having a curved recess therein, said dog having an upturned

end engaging with said recess to limit the swing of the dog.

2. In a garter the combination of a plate having an elongated slot therein; a button 5 having a head thereon for engagement with said slot, a dog pivoted on said plate, said dog being capable of covering part of said slot to hold the button in place in the balance of said slot, said plate having a recess 10 therein concentric to the pivot of said dog, said dog having an upturned end engaging

with said recess to limit the swinging movement of said dog to the length of said recess, said plate having a depression therein opposite to said recess, a projection on said 15 dog, said projection being adapted to engage the depression in said plate to hold said dog temporarily in a predetermined position.

In testimony whereof I affix my signature. 20

ABRAHAM ROSEN.
